UNITED STATES PATENT OFFICE.

LAMARTINE M. FRENCH AND WILLIAM M. O'BRIEN, OF CHICAGO, ILLINOIS, ASSIGNEES
TO ARISTON PIANO-PLAYER COMPANY, OF CHICAGO, ILLINOIS, A CORPORATION OF
ILLINOIS.

PNEUMATIC ACTUATING UNIT.

968,546.

Specification of Letters Patent. Patented Aug. 30, 1910.

Application filed June 23, 1909. Serial No. 503,921.

To all whom it may concern:

Be it known that we, LAMARTINE M. FRENCH and WILLIAM M. O'BRIEN, residing in Chicago, county of Cook, and State 5 of Illinois, have invented certain new and useful Improvements in Pneumatic Actuating Units, of which the following is a complete, clear, full, and precise specification.

10 Our invention relates to pneumatic actuating units for use in pneumatically operated pianos and has for its object more simplified and more compact construction and arrangement. Devices of this class 15 usually comprise a plurality of compartments, some of which are connected with a source of vacuum during operation and others of which at the same time are connected with the atmosphere, and it is desirable for efficient operation that leakage between the compartments be avoided. In 20 pneumatic units of the prior art, the walls and partitions are usually of wood, which is more or less porous and must be especially 25 treated to prevent leakage through its pores. These walls and partitions must also be quite thick to give the necessary strength, the result being that the unit is large and bulky and leaky, unless special packing be 30 provided or other treatment resorted to. A unit also comprises valve mechanism and valve seats. In these prior devices the 35 passage-ways to be controlled by the valves extend through the wooden wall or partition, and the valves must be specially padded, or special bushing mechanism must be provided about the passage-ways so that air tight seating results.

Our invention has for its particular feature 40 the provision of walls and partitions of some tough or resilient and very dense material, preferably in the form of celluloid sheeting. These celluloid walls and partitions can be made very thin and can be cemented rigidly in place. The thin celluloid being flat and practically non-porous and elastic, the valves can engage directly therewith without the necessity of providing leather or other washers or bushings to 45 cushion the valves and to prevent leakage thereby. The engagement of the valves with the celluloid is also noiseless. The unit 50 as a whole is also more compact and much smaller where the thin walls are used.

In the accompanying drawings, which 55 clearly illustrate our invention, Figure 1 is a top view of a pneumatic unit embodying our invention, Fig. 2 is a sectional view taken on plane 2-2, Fig. 1, and Fig. 3 is an enlarged detail view showing the engagement of the valve pin in the valve stem.

The unit comprises a main supporting block 1 at whose rear end is hung the actuating member 2, fabric 3 being secured about the lower edge of the block 1 and 60 the member 2 to form a bellows compartment 4. An extension 5 from the rear edge of the actuating member 2 is adapted for connection with the piano abstract rods either directly or through intermediate 65 mechanism. Cut in the block 1 are the upper and lower diaphragm chambers 6 and 7 separated by the diaphragm 8, and on the block 1 is secured a sheet 9, which is preferably of celluloid or some kindred material, 70 this sheet forming a top flat wall for the upper diaphragm chamber. Secured on top of the sheet 9 is a block 10 whose middle portion is cut away to form a valve chamber 11 whose top wall is formed by the flat 75 sheet 12, also preferably of celluloid or kindred material. A passage-way 13 through the block 1 connects the valve chamber with the diaphragm chamber. In the sheet 9 over the diaphragm is the passage-way 14, 80 and above this passage-way is another passage-way 15 which normally connects the valve chamber with the atmosphere. A valve stem 16 is secured at its lower end 85 to the diaphragm 8 and loosely carries a pin 17 on which is mounted a disk 18, also 90 preferably of celluloid and faced by disks 19 and 20 preferably of sheep-skin. The pin 17 extends upwardly through passage-way 15 and is guided by a bridge piece 21, 95 also of celluloid and cemented to the top of sheet 12. The pin 17 fits loosely in the item 16 so that the valve may have lateral play.

As shown, the unit is supported at its end 100 from the tubular frame 22 forming a chamber which in practice is connected with a vacuum source, the front end of the block extending underneath the frame thereby giving greater volume to the bellows. The upper diaphragm chamber connects with the 105 chamber of frame 22 through the passage-way 23, and the lower diaphragm chamber connects with the tracker-board through the

passage-way 24, pipe 25 and tube 26, the tube having a bleed opening 27 through which the lower chamber also connects with the chamber formed by frame 22.

5 In practice, as the music travels over the tracker-board, the lower diaphragm chamber is connected with atmosphere whereupon the diaphragm is thrown upwardly, the valve carried to open passage-way 14 and to 10 close the atmosphere passage-way 15, and the bellows chamber connecting with vacuum through passage-way 13, valve chamber 11, opening 14, upper diaphragm chamber and passage-way 23. When the tracker-board 15 opening controlling the pneumatic is again closed, the pressure in the diaphragm chambers will equalize through the bleed opening 27 and the diaphragm again follows to carry the valve to its normal position in 20 which the passage-way 14 is closed and the passage-way 15 opened so that the atmosphere can enter and distend the bellows.

The celluloid sheets 9 and 12 can be made very thin, and owing to the density of the 25 celluloid, there will be no leakage there-through. The thin sheets are also very resili- and, therefore, cushion the valves and prevent noise. Owing to this resilient and yielding arrangement, and on account 30 of the loose engagement of the valve pin 17 in the stem 16, the valve uniformly and closely engages the sections about the passage-ways and air-tight fit is assured without the necessity of special washers or bush- 35 ings. The elastic resilient operation is further enhanced by the valve body in the form of a thin celluloid disk. The size and weight of the unit are also very much de- creased by using these thin walls.

40 Another important feature is that the celluloid cement which gives a more yielding joint than ordinary glue, and which, therefore, prevents a separation of the parts due to unequal expansion or contraction. The 45 celluloid will not warp as will wood, and consequently the valve and valve seats will always retain their true form. There are also other advantages which celluloid or kindred material possess over wood.

50 Having thus described our invention, we desire to secure the following claims by Letters Patent.

1. In a pneumatic unit of the class de- 55 scribed, the combination of walls forming compartments, passageways through said walls, and a valve for controlling said passageways, each wall being in the form of a thin, flat celluloid sheet against whose flat surfaces the valve directly engages.

60 2. In a pneumatic device of the class de- scribed, the combination of a hollow block forming a valve chamber, a thin flat sheet of celluloid secured to said block to form a wall for said compartment, a passage-way 65 through said wall, and a valve in said com-

partment for seating directly against said wall about the flat surface of said passage-way.

3. In a pneumatic device of the class de- 70 scribed, the combination of a hollow block forming a chamber, a thin flat sheet of celluloid secured to the block and forming a wall for said chamber, there being an opening through said wall, and a valve in the 75 form of a celluloid disk for seating against the flat surface of said wall to control said opening.

4. In a pneumatic device of the class de- 80 scribed, the combination of a hollow block forming a chamber, a thin flat sheet of celluloid secured to the block and forming a plain flat wall for said chamber, there being an opening through said wall, a valve in the 85 form of a celluloid disk for seating directly against the flat surface of said wall to control said opening, a stem for said valve, and a guiding bridge for said stem, said bridge being in the form of a celluloid strip cemented across said opening and to said celluloid wall.

5. In a pneumatic device of the class de- 90 scribed, the combination of a hollow block forming a valve compartment, a thin flat sheet of celluloid secured to said block to form a wall for said compartment, said wall 95 having an opening, a valve in said compartment for seating directly against the flat surface of said wall about said passage-way, a diaphragm below said compartment, a stem extending from said diaphragm, and a 100 supporting pin for said valve having loose engagement and lateral play in said stem whereby said valve may uniformly engage said wall.

6. In a pneumatic device of the class de- 105 scribed, the combination of a block having a diaphragm compartment, a diaphragm stretching across said compartment, a stem secured to the diaphragm, a wall forming a 110 valve seat, a valve, and a supporting pin for said valve, said stem having a longitudinal opening of slightly greater diameter than said pin for loosely receiving the end of said pin whereby said valve is free to seat accurately against said wall upon movement of 115 the diaphragm.

7. In a pneumatic unit of the class de- 120 scribed, the combination of a hollow block forming a valve compartment, a sheet of thin, smooth, elastic and dense material 125 covering said block to form a flat wall for said compartment, said wall having an opening, and a valve in said compartment for seating directly against the flat surface of said wall about said opening.

8. In a pneumatic unit of the class de- scribed, the combination of a main block having a diaphragm compartment, a dia- 130 phragm extending across said compartment, a hollow block on said main block, a sheet of

- thin, smooth, dense and elastic material secured between the blocks, a second sheet of thin, smooth, dense and elastic material secured to the top of the hollow block, said 5 first mentioned sheet forming an upper flat wall for the diaphragm compartment and said first and second sheets forming a valve chamber with the hollow block, there being an opening through the first mentioned sheet 10 leading from the valve compartment to the diaphragm compartment and an opening in the second mentioned sheet registering with the first mentioned opening, and a valve in said compartment connected with the dia- 15 phragm to be raised and lowered upon actuation of the diaphragm and to engage directly and with air-tight fit against the flat surfaces of the sheets to control the openings therethrough.
- 20 9. In a pneumatic unit of the class de- 25 scribed, the combination of a main block having a diaphragm compartment, a dia- phragm extending across said compartment, a hollow block on said main block, a sheet of thin, smooth, dense and elastic mate-
- rial secured between the blocks, a second sheet of thin, smooth, dense and elastic mate- 30 rial secured to the top of the hollow block, said first mentioned sheet forming an upper flat wall for the diaphragm compartment 35 and said first and second sheets forming a valve chamber with the hollow block, there being an opening through the first men- 40 tioned sheet leading from the valve com- partment to the diaphragm compartment and an opening in the second mentioned sheet registering with the first mentioned opening, and a valve in said compartment connected with the diaphragm to be raised and lowered upon actuation thereof, said 45 valve being in the form of a flat disk having the same properties as the sheets whereby said valve may engage directly and with air-tight fit with the flat surfaces of the sheets to control the openings therethrough.
